UNITED STATES PATENT OFFICE.

CHARLES S. BURTON, OF OAK PARK, ILLINOIS, ASSIGNOR TO STEWART-WARNER SPEEDOMETER CORPORATION, OF CHICAGO, ILLINOIS, A CORPORATION OF VIRGINIA.

VACUUM FUEL-FEED DEVICE.

1,348,084.

Specification of Letters Patent. Patented July 27, 1920.

Application filed August 16, 1918. Serial No. 250,115.

To all whom it may concern:

Be it known that I, CHARLES S. BURTON, a citizen of the United States, and a resident of the village of Oak Park, in the 5 county of Cook and the State of Illinois, have invented certain new and useful Improvements in Vacuum Fuel-Feed Devices, of which the following is a specification, reference being had to the accompanying 10 drawings, forming a part thereof.

The purpose of this invention is to provide an improved construction of vacuum fuel feed devices for internal combustion engines which shall be particularly adapted 15 for furnishing the fuel lifted from a low-level main supply tank when the suction available is low, in small quantities and short intervals as it is thus lifted, and otherwise to adapt the device to have greater 20 feeding and storage capacity within given over-all dimensions. It consists in the elements and features of construction shown and described as indicated in the claims.

In the drawings;

25 Figure 1 is a vertical section of the upper portion comprising the entire valve controlling connections and operating float of a device embodying this invention, the lower part of the float chamber and the reservoir 30 chamber being broken away.

Fig. 2 is a section in a plane at right angles to that of Fig. 1, showing the same construction, with a middle portion of the vertical extent of the reserve chamber 35 broken away, to reduce the compass of the view.

Fig. 3 is a section at the line 3-3 on Fig. 1.

40 Fig. 4 is a section at the line 4-4 on Fig. 1, looking upward.

Fig. 5 is a detail section at the line 5-5 on Fig. 4, looking radially inward.

The problem the solution of which is attempted in this invention, is to adapt a vacuum fuel feed device of the type comprising a vacuum chamber and a reserve chamber, and which derives the suction for operating it from the manifold of the engine which is to be served, to release and deliver 50 to the reserve chamber the liquid fuel which is sucked up from the main low-level supply tank into the vacuum chamber, at the shortest practical intervals, when the condition is such that the supply is low and

the suction light; these two conditions being usually concurrent, that is the suction being light whenever the conditions have for some time been such as to reduce the reserve supply to a low point.

In the familiar devices for this purpose 60 now in common use, there is employed what is known as a "snap action" for causing a quick reversal of the situation of the valves which control the dominance in the vacuum chamber of atmospheric pressure or suction. 65 This snap action is constructed to cause the change of level of the liquid in the vacuum chamber, by means of the float therein, to shift certain valve-operating lever connections with which the snap-spring is connected, as the float rises or falls, moving one connection of the spring until its line of reaction extends past the fulcrum of the lever connected thereto, the spring at this stage being at maximum tension, and therefore reacting to continue the throw of the levers in the direction in which they have been moving to thus tension the spring. In such structure the reacting spring furnishes 70 the sole mechanical force for moving the valve or valves to be shifted; and since the valves in question are held by the suction in resistance to the movement to be thus caused, the spring must be constructed to have at this stage of maximum tension adequate tension to move the valves against the maximum suction; because obviously the spring tension is constructional, and will not be changed by the changing conditions of suction, but must be adequate for 75 the extreme conditions which may arise.

Now, in any construction in which the valve levers are actuated only by the springs, and the float obtains no direct action on the valve-operating connection, inasmuch as the tension of the snap-spring is overcome by the buoyancy or weight of the float in causing the reversion of the valve situation, and the operative buoyancy or operative weight of the float depends on 80 the extent to which the float is depressed in, or held up out of the liquid by the spring resistance, there cannot be any variation in the height to which the liquid must rise or the depth to which it must fall in order to 85 reverse the valve situation; and the quantity of liquid taken in and delivered at each 90 cycle of the operation of the device, must

always be the same whatever be the suction operating, and whatever the condition of the device as to reserve supply. It follows that in such a structure the purpose of the 5 present invention, namely, as above stated, to adapt the device to receive and deliver small charges to the reserve chamber, so as to make such deliveries quickly when the reserve supply is low, can only be accomplished by making the structure so that small charges shall be received and delivered at all times and under all circumstances.

It will also be evident upon consideration, 10 that with a given rise and fall of the liquid level in the vacuum chamber requisite for reversing the valve action, the frequency of such change, which depends upon the quantity of liquid going in and out to make the 15 change, can be increased,—that is the quantity can be reduced,—by reducing the cross-section of the vacuum chamber in which the liquid level rises and falls in such change, or by reducing the amount of such change 20 of level, that is, the vertical dimension of the space thus filled and emptied. And it will be further observed that the cross-section of the space in the vacuum chamber thus filled and emptied depends upon the 25 difference in cross-section of the chamber itself and the cross-section of the float operating therein, and can be reduced, therefore, only by causing these two cross sections to approximate each other, that is by reducing 30 the width of the space in the chamber around the float. And it will be further observed that the reduction of the change of level occurring at each reversal of the 35 valve situation with a float of a given cross-section, can be reduced only by reducing the spring resistance against which the float operates.

All these considerations enter into the 40 problem and into the solution of it which is embodied in the structure shown, which will now be described.

In the structure shown in the drawings, 1 is the reservoir or reserve chamber of the device; 2 is the vacuum chamber which is 45 suspended in the reservoir or reserve chamber, 1, having for that purpose at its upper end a horizontal flange, 2^a, which laps upon an interiorly protruding flange, 1^a, of the chamber, 1. 3 is a cap member which covers 50 both chambers and has a flange, 3^a, which laps upon the margins of the flanges, 1^a and 2^a, which are bound to said flange, 3^a, by bolts, *a*, thereby securing the three principal members of the structure firmly together, 55 suitable packing being interposed between said flanges for making the joints liquid-tight. 4 is a check valve past which the liquid is discharged into the reserve chamber.

5 is a buoy in the vacuum chamber con-

stituting part of the means for alternating the dominance of suction and atmospheric pressure in that chamber, hereinafter more particularly described, being the means for reversing the valve situation upon change 70 of level of the liquid in the vacuum chamber. This buoy is calculated as to relative weight and volume to balance upon submersion in the liquid fuel to the depth indicated by the dotted line, *m*, on said buoy, and to have 75 operative buoyancy adequate for overcoming the resistance of the snap-action spring hereinafter described, upon being further submerged to the line, *n*, and to have operative weight sufficient for overcoming the 80 resistance of the snap action spring upon being un-submerged or held up while the liquid level falls to the line, *p*.

The buoy, 5, is suspended in the vacuum chamber by means of a bell crank lever, 6, 85 whose horizontal arm is in the form of a bail embracing the buoy from one side, and whose vertical arm extends downward from the fulcrum of the lever which is fulcrumed on the wall of the vacuum chamber most conveniently at 7^a on lugs 7, 7, depending from the cap member, 3. 8 is the snap-action spring which in the construction illustrated, is a compression spring coiled about a guide link or stem, 9, which 90 is pivoted by its head, 10, at its lower end between lugs, 7—7, which depend rigidly from the cap 3, the upper end of the stem passing loosely through the cross-neck connecting the two parallel downwardly extending arms, 6^a, of the bell-crank-lever 6, so that said link or stem 9 has sliding pivotal engagement with said lever arm. The bail member of the bell-crank-lever engages trunnions 5^a at opposite sides of the float, the 95 chord of the arc of movement of the axis of the pivotal connection of the lever to the float at the trunnions being substantially vertical, so that the lateral or horizontal displacement of the float in the swing of 100 bell-crank-lever is negligible. 12 is a second bail which embraces the float vertically, extending up around the lower end of the float and having its ends engaged with the trunnion, 5^a, by which the bell crank lever 115 is connected to the float, the ends of the bail, 12, being slotted at 12^a, for their engagement with their trunnions to provide for lost motion between the float, and thereby between the bell crank lever,—and 120 the said bail, 12, the length of the slots and the extent of this lost motion being designed to be substantially the amount of the throw of the bell crank lever at the ends of its bail member from the intermediate position at which the snap-spring is aligned with the bell crank lever fulcrum, to the limit of the throw caused by the spring in either direction from this middle position. 125 The bail 12, is pivotally connected with a 130

lever 13, which extends across under the lower end of the buoy, 5, being itself in the form of a bail, that is, having both ends upturned alongside the buoy, one end being fulcrumed at 14 on the wall of the vacuum chamber, and most conveniently on the lower ends of the lugs, 7, 7, depending from the cap 3. The other end which extends up to substantially the same level as the fulcrum,—that is, at the mid-position of the throw of the lever,—is rigidly attached to a substantially horizontal cross-head, 15, which engages loosely,—but substantially without lost motion except as slight pivotal motion is permitted,—the stems of the suction controlling valve, 16, and the atmosphere inlet valve, 17, controlling respectively, the suction outlet, 18, and atmosphere inlet, 19, formed in the cap member, 3, which closes the vacuum chamber at the top.

For obtaining the desired compactness of construction, so as to have within given dimensions over all a maximum storage capacity of the entire device, and at the same time 25 the possibility of occupying said maximum capacity with the liquid, and adapting the device to deliver minimum charges with maximum frequency from the vacuum chamber to the reserve chamber, the construction 30 shown involves certain details requiring particular mention.

Space in the vacuum chamber is obtained for the spring-snap action involving the bell crank lever with its downward extending arm 6^a, the spring 8 with its guide and stop and space for the swing or throw of the bell crank lever arm and spring, and all this with the minimum enlargement of the liquid capacity of the vacuum chamber 40 around the float, by forming the vacuum chamber with a pocket or outwardly extending recess 30 at one side, intruding into the annular space between the outer wall of the reserve chamber and the wall of the 45 vacuum chamber at the upper end of said space at one side, this pocket being radially extended as far as it may be consistently with leaving room for the flange 2^a of the vacuum chamber to seat upon the inturned flange 1^a of the reserve chamber, as already 50 described. At the opposite side of the buoy, the vacuum chamber is provided with a similar pocket 20 dimensioned radially substantially the same as the pocket 30, but extending circumferentially with respect to the vacuum chamber and reserve chamber a sufficient distance to accommodate the atmosphere valve 17, suction valve 16, and the ports respectively which they control, with 55 adequate distance between them to accommodate on the outside of the chamber above the shoulder hereinafter mentioned, the necessary fittings for connections with the said ports. The cap member 3 contains the upper part of the vacuum chamber which is re-

duced in diameter so as to exceed the diameter of the float only by a sufficient amount to afford necessary clearance for the free movement of the latter up and down. This causes the said cap 3 to require at its 70 lower end for its junction with the members 1 and 2 of the structure, the flange 3^a above mentioned, whose outer diameter is the same as the outer diameter of the member 1, so that it laps upon the top of the marginal flanges of said other two members 1 and 2. This flange thus overhangs the pockets 30 and 20, and through it there are formed the two ports mentioned, viz: suction outlet port 18, atmosphere inlet port 19, and said 75 cap is formed with a segmental boss 3^c of sufficient circumferential extent to embrace these two ports which are bored in the boss from the upper end, the ends of the bores being plugged as shown, and the bores 80 being tapped laterally for the necessary connections, namely the suction pipe 25 leading to the suction port, and the atmospheric inlet pipe 28; and the same boss 3^c is extended inwardly over the head of the cap to accommodate the fuel inlet port 21, which is bored into the boss radially to meet a vertical bore from the under side of the cap, as seen in dotted line in Fig. 5, and in full line as to its mouth in Fig. 4. The outer end of 85 this radial bore affords connection for the fuel supply pipe 23, which leads from the main tank. This boss is extended at 27 over the flange radially, to overhang the annular interval between the vacuum chamber and 90 the reserve chamber to afford opportunity for atmospheric connection by the duct 27^a, from the top of the reserve chamber into the atmosphere inlet passage leading to the 95 vacuum chamber above the atmosphere valve, as has been customary in devices of this character heretofore, for convenience of connecting both said air passages with a single air pipe 28 which may extend to any 100 desired height or to any desired point at a distance, for the discharge of any vapor of the liquid fuel which may be generated in either of the chambers under conditions causing the device to become highly heated.

The operation of the device in view of the 105 construction described and the dimensions of the float for operative buoyancy and weight as above described, is as follows:

Assuming the entire device empty and connected with a suction resulting in producing 110 a partial vacuum in the vacuum chamber and causing the inflow of liquid fuel from the main low tank into the vacuum chamber, the latter being filled to a level which will first cause the buoy to be submerged to the balance line $m-m'$; and then as the liquid further rises in the vacuum chamber to a certain level indicated by the line, n , will cause the buoy to rise with it against the resistance of the snap-action spring 8, while the buoy held 115

down by the resistance of that spring becomes submerged more deeply notwithstanding it will be found to have been lifted to the position shown in dotted line in Fig. 1 5 (but less, it will be observed, than the rise of the liquid level), at which position the snap-action spring 8 is under the maximum tension, the bell crank lever arm 6^a being alined with said spring.

10 At this position the excess of rise of the liquid level from the buoy-balancing position indicated by the line, *m*, over the rise of the buoy during said rise of the liquid will be an amount dependent largely upon the 15 tension of the spring, 8. Upon the liquid rising an appreciable amount above this level, the reaction of the snap-action spring 8, which occurs upon the lever arm 6^a being carried past the position of alinement with 20 the spring, will cause the buoy to be lifted to the position shown by line, *r*, in Fig. 5, unless the suction operating upon the atmosphere valve 17 which is up to that time closed, (the suction port and valve being 25 open), is more than can be overcome by the re-action of said snap-action spring. It is intended that this spring shall be of such a tension as to open the atmosphere valve under 30 conditions of the lowest suction under which the device will properly function or is expected to be operated, or at least under some relatively low suction. If the suction is still lower than this, the valve will all the more certainly be opened by the re-action of 35 the spring at the point indicated. If the suction is greater than the minimum at which the snap-action spring is designed to operate for such opening of the valve, the snap-action connection being carried past the center 40 so that the spring is in position to react, the further movement of the bell crank lever and the further rise of the float will be halted until further rise of liquid in the vacuum chamber, causing deeper immersion of 45 the buoy in the liquid and greater effective buoyancy of the float, renders that buoyancy sufficient to overcome the suction on the atmosphere valve; whereupon, such point being passed, the valve will yield and snap 50 open to the full extent, the bell crank lever completing its swing in the direction for such opening and the float rising to the position shown by dotted line in Fig. 2, which is the high position of the float and the 55 limit of its upward range of movement.

The valve situation being reversed by this movement of the float, that is to say, the suction valve being closed and the atmosphere valve opened, the contents of the vacuum chamber will descend by gravity past the outlet valve 4 into the reserve chamber 1. As the level of liquid in the vacuum chamber falls, the buoy will fall with the liquid level but substantially half as fast as 60 the level falls, because it will fall against

the resistance of the snap-action spring 8, until by this resistance the float has become unsubmerged by being held up while the liquid level was falling to the line *p*—*p* on the float; and upon the further fall of liquid 70 an appreciable increment below this point, the accumulated effective weight of the float overcoming the resistance of the snap-action spring 8, will carry the bell crank lever arm 6^a past the position of alinement with the 75 spring, and the spring will complete the throw carrying the bail member of the bell crank lever down and permitting the float to descend to the low-level position shown in full lines in Fig. 1, again reversing the 80 valve situation, that is, closing the atmosphere valve and opening the suction valve. Inasmuch as in this action the suction valve will have to be pulled off its seat against the suction, it will be seen that if the suction hold on this valve is greater than can be overcome by the reaction of the snap-spring 8, the descending movement of the float will be halted at the position of maximum tension of the spring, that is to say 90 at the point at which the trunnions 5^a reach the lower end of the slots, 12^a, in the bail 12, and the parts will there remain until further fall of the liquid level has rendered the 95 effective weight of the float by reason of its further unsubmergence, sufficient to overcome this suction pull, then the action will be completed, the float completing its descent to the low limit above mentioned. It will be seen therefore, that the change of 100 liquid level occurring in each cycle of the operation of the device will have a minimum determined by the tension of the snap-spring, said tension being designed, as above stated, with reference to a certain assumed 105 minimum suction operating from the valve; and that it will have a maximum determined by the deepest submersion and the highest emersion of the buoy, the submersion for said minimum being when the buoy 110 is positioned at the halting point in the rising movement,—that is, when the snap-action spring is alined with the bell crank lever arm, 6^a, and the emersion for said minimum being when the float reaches the 115 halting point in its descent. The maximum change of the level will therefore be the full height of the float, while the minimum will be the distance between the lines, *m* and *p*; and that the minimum change of 120 level will occur under conditions of low suction. It will be seen also that the continuance of conditions of low suction while the reserve chamber contains a low reserve supply, that is, anywhere below the bottom 125 of the vacuum chamber, will result in corresponding frequency of repetition of the filling and discharging action of the vacuum chamber; that is to say, the vacuum chamber will make deliveries at short inter- 130

vals corresponding to the short interval necessary for taking a small supply at each cycle.

Although the theoretical maximum high level of liquid in the vacuum chamber is as above stated, the parts are designed and proportioned to prevent the real maximum high level from rising above the level of the suction and atmosphere ports, 18 and 19, that is to say, the submergence of the float to the extent to which it will be submerged by the rising of the liquid level to a point somewhat below the level of these ports, is calculated to make the uplift of the buoy sufficient to overcome the maximum suction on the atmosphere valve which will at any time be operating in a device of this kind in actual service, wherein, according to actual experience, the suction derived from the engine manifold may be assumed as never exceeding twenty-two (22) inches of mercury, and seldom exceeding eighteen (18) inches. The suction-hold on the suction valve may safely be assumed as considerably less than the suction pull on the atmosphere valve for the same conditions of suction, because of the fact that the suction port is usually considerably smaller than the atmosphere port; and for that reason, in the structure as shown in the drawings, the range of fall of level of the liquid along the float below the line p to the very bottom of the float is not shown as great as the range of change of level possible from the line m up to the level of the ports mentioned; but it will be readily understood that the float proportions may be designed so as to allow for as much fall below the line p as there is allowed for rise above the line m , as will be necessary if the suction port is made as large as the atmosphere port.

One of the features in reducing the charge received and delivered by the vacuum chamber at each cycle to the lowest point, is the reduction of the distance between the high and low levels to the minimum under conditions of low suction, as explained. Another factor is the reduction of the cross-section of the space in the vacuum chamber which is evacuated and filled at each action, this cross-section being dependent upon the relative diameters of the float and the vacuum chamber at the part of the height of the vacuum chamber from which the float withdraws and into which it intrudes in each action; and inasmuch as it is evident that the reserve chamber can never be filled to a greater distance above the low-level of the vacuum chamber than it can be filled by the amount of one charge delivered to it from the vacuum chamber, it becomes a part of the problem to properly relate the dimensions which determine the amount of the minimum charge

to the dimensions of the interspace between the vacuum chamber and the reserve chamber wall at and above the plane of the low-level of the vacuum chamber. This problem must be solved consistently with the further requirement that space must be allowed above the maximum level to which the liquid can be raised in the reserve chamber for the expansion of liquid which is liable to occur when the device becomes heated when the chambers are full to this high level.

Upon inspection of the structure shown in the drawings, it will be seen that with a view to avoiding a large cross-sectional area of the space in the vacuum chamber around the float therein throughout the range of height of the liquid between high and low levels at maximum suction, the space required for the valves and for the snap-action,--namely, the pockets 30 and 20,--is provided by means of these pockets, in preference to an enlargement of the diameter of the chamber throughout which would otherwise be the only obvious means of providing the necessary space. It will be observed also that by limiting the increased diameter of the chamber to the circumferential extent of these pockets, and by extending the pockets only part-way to the outer wall of the reserve chamber, there is provided an upwardly extending space in the reserve chamber above the maximum high level of the liquid therein, for the expansion, and there is also obtained the possibility which is taken advantage of in the manner above described, of connecting the highest point of the reserve chamber directly with the atmosphere inlet above the atmosphere valve as is done by means of the duct 27^a in the boss 27, located above the segmental extent of the pocket 20.

It will be further observed that by locating the operating lever for the valve below the float, there is avoided the necessity for extending the vacuum chamber higher than necessary to merely accommodate the float at its highest position, as would be necessary if the levers were extended above the float instead of below it, and thus the maximum extent of the device over-all vertically is reduced without reducing its capacity, since any space above the float could not be liquid containing space, and therefore, would not add to the capacity. It will be observed also that by hanging the float in the manner described, so that at its highest position it extends above the highest level to which the liquid can ever be permitted to rise,--namely, a plane a little below the suction and atmosphere ports,--a distance equal only substantially to the throw of the float, that is, so that the float may, in the case of maximum suction, be fully submerged and thereby exert its maxi-

mum lifting force, and providing a pocket for this upper end portion of the float entirely above the level of said valved ports, and by reducing the diameter of the chamber at this point to the minimum which will accommodate the float and avoiding the positioning of any of the operating elements in the space around the float which would increase the requirement of the diameter, 5 for their accommodation, there is provided the shoulder above which all the fluid connections can be made, so that these fluid connections are all brought within a maximum compass over-all which is no greater than 10 required for the chambers without these connections.

The total result of the several detail features of construction above pointed out is that the entire device within a given compass over-all in both vertical and horizontal directions has substantially the maximum capacity for the liquid fuel under the conditions under which it may be filled to maximum capacity, and has a pre-determined minimum of the liquid charge received and delivered at each cycle of the action under the conditions requiring frequency of such action.

I claim:

30 1. In a vacuum fuel feed device comprising a vacuum chamber and a reserve chamber, the vacuum chamber having the following fluid connections, viz: (1) a fuel supply inlet, (2) a fuel supply outlet to the reserve 35 chamber, (3) a suction outlet, and (4) an atmosphere inlet; means in the vacuum chamber for alternating the dominance of suction and pressure comprising a buoy mounted for movement by change of liquid 40 level in said vacuum chamber; a valve device controlling certain of said fluid connections, and operating connections to the valve device from the buoy comprising a snap-action spring, the buoy being positively connected operatively with the valve device independently of the snap-action spring; said operating connections containing a lost motion joint; the snap-action spring being connected for its tensioning by the movement 45 of the buoy through the range of said lost motion.

2. In a construction such as defined in claim 1, the buoy being pivotally suspended and having two connections from its suspension pivots, one consisting of a lever having its fulcrum support on the vacuum chamber wall, the snap-action spring operating on said lever, the other extending to the valve and containing the lost motion 50 joint.

3. In a construction defined in claim 1 foregoing, the buoy being carried by two lifting elements the snap-action spring being connected for operating on one of them, and the other containing the lost-motion 55 joint.

4. In a construction defined in claim 1 foregoing, the buoy being pivotally suspended, and having two connections from its suspension pivots, one of said connections comprising a bail embracing the buoy horizontally, and the other comprising a bail embracing it vertically. 70

5. In a construction defined in claim 1 foregoing, the buoy being pivotally suspended and having two bails for so suspending it,—one bail embracing it vertically and the other bail embracing it horizontally, the vertical bail being positioned and connected to embrace the buoy from below by upward extending arms; whereby the same and the connections therefrom for operating valves are accommodated in space necessarily provided for the liquid, to the avoidance of special provision for such accommodation. 75

6. In a construction defined in claim 1, foregoing, the buoy being pivotally carried, the carrying means comprising two bails, one embracing the buoy horizontally and the other embracing it vertically from below upward, the operating connections for the last mentioned bail to the valve consisting of a lever fulcrumed on the vacuum chamber wall at one side of the buoy and having its engagement with the valve at the opposite-side, and having a droop to reach the bail connection and accommodate the float between its fulcrum and its valve connection. 80

7. In a construction defined in claim 1, 100 foregoing, the vacuum chamber being extended and protruded above the top of the reserve chamber with reduced diameter to accommodate the buoy at the elevated position of the latter, the valved fluid connections being made at the shoulders which results around such extension. 105

8. In a construction such as defined in claim 1, the vacuum chamber being extended and protruded above the top of the reserve chamber with reduced diameter to accommodate the buoy at the elevated position of the latter, valve fluid connections being made at the shoulder resulting around such extension. 110

In testimony whereof, I have hereunto set my hand this 12th day of August, 1918, at Chicago, Illinois.

CHARLES S. BURTON.
